EMBROIDERY MECHANISM

Joseph C. Gilardone, Fleetwood, Pa.

Application March 22, 1937, Serial No. 132,378

10 Claims. (Cl. 112—95)

This invention relates to embroidery machines, and more particularly to the shuttle means of the stitching mechanism of such machines, and which is cooperatively associated and coacts with fabric or hosiery holding devices of the type disclosed in my Patent No. 1,482,680, and my copending patent application Serial No. 132,379 filed of even date herewith.

Among the objects of my invention are, to provide novel shuttle means for embroidery machines which operates more efficiently, freely and precisely than the means heretofore available for this purpose, and which makes it possible to obtain better results from machines, such as hosiery embroidery machines, to which my invention is particularly applicable.

With these and other objects in view, which will become apparent from the following detailed description of the illustrative embodiments of the invention shown in the accompanying drawings, my invention comprises the novel elements, features of construction and arrangement of parts in cooperative relationship, as hereinafter more particularly pointed out in the claims.

25 In the drawings:—

Figure 1 is a front elevational view of my novel shuttle means, illustrated in association with other parts of a hosiery embroidery machine with which it is adapted to cooperate;

30 Fig. 2 is a side sectional view, taken substantially as indicated by the arrows 2—2 on Fig. 1; Fig. 3 is a rear elevational view of Fig. 1, and shows certain of the parts in another position;

Fig. 4 is an enlarged sectional view taken substantially as indicated by the arrows 4—4 on Fig. 2;

Fig. 5 is a cross sectional view, taken as indicated by the arrows 5—5 on Fig. 4; and

Fig. 6 is an enlarged detail sectional view, taken as indicated by the arrows 6—6 on Fig. 1.

For illustrative purposes, a practical form of my invention will be hereinafter described as embodied in well known hosiery embroidery machines. In such machines, a multiplicity of individual hosiery holding frames or devices are simultaneously moved as a unit by patterning means with respect to cooperatively associated embroidery stitching mechanism which functions to produce similar clocks, or other ornamentations, in each of the stockings on the frames. The hosiery holding frames, or devices, are generally of a rectangular shape and are open at the front, rear and bottom so that each device may be positioned vertically over its respective shuttle arrangement of the machine. When a stocking

is properly mounted on one of these hosiery holding devices the hosiery fabric at the front open side of the device is positioned between the shuttle arrangement and its cooperating stitching needle.

When the machine is in operation, all the stocking holding frames are moved as a unit in accordance with pattern controlled means, relative to the stitching mechanism which is mounted in fixed position, and in this manner the same designs are embroidered in all the stocking fabrics. 5

After a design has been embroidered in one side of the stocking, each frame is reversed so that the fabric extending over the rear open end of the frame comes between its respective shuttle mechanism and needle, and the embroidering 10 operation is repeated.

My invention is concerned with the shuttle mechanism of the general type referred to.

In the accompanying drawings, only those well known parts of a hosiery embroidery machine are 20 shown in association with my invention which are helpful to an understanding of the function and operation of the invention. For additional information concerning correlated and associated parts of the machine, reference may be had to my 25 above mentioned patent and patent application.

Referring to the various figures of the drawings, 10 designates a tubular standard or support, which is provided at its lower end with a base plate 11, and at its upper end with an angularly 30 positioned guide block 12, for a shuttle 13 and shuttle mounting 14 both of which are arranged to be reciprocated in a guideway 12a of the guide block 12 during operation of a needle 15 back and forth through the hosiery fabric, indicated by the 35 numeral 16, as it enters and is withdrawn from its guide slot 17 in the guide block 12 during cooperation with the shuttle 13.

The base plate 11 is secured by means of bolts 18 and nuts 19 to a fixed bar 21 which extends the 40 full length of the machine and has as many additional shuttle devices similarly mounted thereon as desired.

Reciprocation of the shuttle 13, and its mounting 14, is effected by means of an actuator or bar 45 22, which also extends the full length of the machine and cooperates with the other shuttle devices in similar manner. The actuating bar 22 has a uniform but limited composite movement vertically and horizontally with respect to the 50 shuttle device, and the vertical component of this movement is transmitted to the shuttle 13 and its mounting 14 by means of a movement transmitting member, or slide rod 23, and a motion translating element or link 24 which is 55

pivotedly connected at 25 with the rod 23, and at 26 with the shuttle mounting 14. Fig. 1 shows actuator rod 22 substantially in its lower or extreme position when moved in one direction, and Fig. 3 in its other, or extreme upper position.

5 The rod 23 is arranged to freely slide in a guide 27, integrally formed on the support 10, and a guide aperture 28 in base plate 11, a compression spring 29 being provided on the rod 23 intermediate the guide 27 and an adjustable collar 31 fixed to the rod 23 by a set screw 32. The spring 29 acts to urge the rod 23 downwardly against the lifting action of the actuator 22, and its pressure may be regulated, as desired by selectively positioning the collar 31 on the rod 23.

10 In order that the shuttle 13 may be properly positioned for most efficient cooperation with the needle 15, the rod 23 is provided with a rod length adjusting sleeve 33 which is internally threaded as at 34 and mounted on the lower threaded portion 23a of the rod 23, a lock nut 35 being provided for locking and unlocking the sleeve 33, as desired. An anti-friction roller 36 is rotatably secured to the lower extremity of the sleeve 33, 15 and is adapted to at all times rest on the actuator bar 22, and during movement of the latter to rotate so as to reduce the contact friction between these parts to a minimum.

15 The shuttle mounting 14 is provided at its lower end with a cross pin 37 against which the shuttle 13 rests, and a pivotally mounted finger 38 at its upper end. The finger is ordinarily positioned crosswise of the mounting 14, as shown in Fig. 5, to prevent the shuttle 13 from escaping 20 or flying out of the top of the mounting 14 during its reciprocatory movements. When it is desired to remove the shuttle 13 to permit replacement of the yarn bobbin (not shown) within the same, or for other reasons, the finger 38 is moved 25 to its vertical position indicated by the dot-and-dash lines in Fig. 4. A leaf spring 39 secured to the side of mounting 14 by a screw or rivet 41 cooperates with the pivoted end of finger 38 to yieldably hold the same in either the vertical or 30 horizontal positions indicated in Fig. 4.

25 To facilitate precise and easy sliding action of the mounting 14 in its guideway 12a of the guide block 12, the mounting 14 is provided with a rib 42 which extends lengthwise of the mounting 14 35 and is arranged to slide in a groove 43 of the block 12.

30 The upper part of my novel shuttle device extends upwardly into a fabric or hosiery holding frame 45, as usual, so that the fabric, indicated 35 at 16 in Fig. 2 may be embroidered when the needle 15 and shuttle mechanism cooperate during operation of the machine, all as well understood by those skilled in this art.

35 The frame 45 is constructed and mounted on a pattern actuated bar 46, as explained in my above referred to patent and patent application.

40 During operation of the machine, the movements of the needle 15 and the actuator 22 are cooperatively synchronized with the movements 45 of the hosiery holding frame 45 to effect embroidery of a clock or other design in the fabric 16. It will be understood that although I have only illustrated one shuttle means in the drawings, as many similar means may be provided in 50 the embroidery machine, as desired, all operated in unison, and each coacting with its respective needle mechanism and hosiery frame in the manner described, and set forth in my above mentioned patent and patent application.

45 75 Of course, my improvements in shuttle mech-

anisms, as specifically shown and described in connection with hosiery embroidery machines, can be changed and modified in various ways without departing from the invention herein disclosed and hereinafter claimed.

5

I claim:

1. In an embroidery machine, the combination with pattern controlled fabric positioning means; of embroidering mechanism comprising a yarn shuttle; a movable shuttle mounting; a guide for determining the movement of said mounting; and means for actuating said mounting including an actuator, a movement transmitting member movable at an angle with respect to the movement of said mounting, and a motion translating element connecting said member and mounting.

10 2. In an embroidery machine, the combination with pattern controlled fabric positioning means; of embroidering mechanism comprising a yarn shuttle; a movable shuttle mounting; a guide for determining the movement of said mounting; a base for said mounting provided with a guide for a movement transmitting member; and means for actuating said mounting including an actuator, a motion transmitting member movable in said guide at an angle with respect to the movement of said mounting, a motion translating element connecting said member and mounting, and resilient means for yieldably urging the movement transmitting member against the actuator.

15 3. In an embroidery machine, the combination with pattern controlled fabric positioning means; of embroidery mechanism comprising a yarn shuttle; a movable shuttle mounting; a guide for determining the movement of said mounting; a base for said mounting provided with guide means for a movement transmitting member; and means for actuating said mounting including an actuator, a motion transmitting member provided with 20 length adjusting means and movable in said base guide means at an angle with respect to the movement of said mounting, and a motion translating element connecting said member and mounting.

25 4. In an embroidery machine, the combination with pattern controlled fabric positioning means; of embroidery mechanism comprising a yarn shuttle; a movable shuttle mounting; a guide for determining the movement of said mounting; a base for said mounting provided with guide means for a motion transmitting member; and means for actuating said mounting including an actuator having a composite movement, a motion transmitting member provided at one end thereof with length adjusting means having an anti-friction device and arranged to move in said base guide means at an angle with respect to the movement of said mounting, a spring for yieldably urging the anti-friction device against said actuator; and a motion translating element connecting said member and mounting.

30 5. In an embroidery machine, the combination with pattern controlled fabric positioning means; of embroidering mechanism comprising a yarn shuttle; a movable shuttle mounting; a guide for determining the movement of said mounting; a base for said mounting provided with two guides for a slide rod; a slide rod 35 movable in said guides having a threaded portion; a rod length adjusting sleeve cooperatively associated with said threaded portion; a collar secured to the slide rod intermediate the rod guides; a compression spring on the slide rod 40

75

- intermediate one of the slide rod guides and said collar; a link connecting the slide rod and shuttle mounting; and an actuator for imparting movement to the slide rod.
6. In an embroidery machine, the combination with pattern controlled fabric positioning means; of embroidering mechanism comprising a yarn shuttle; a movable shuttle mounting; a support for said mounting provided with a slide-
10 way for the shuttle mounting; a guide member on the shuttle mounting; a guide member on the mounting support arranged to cooperate with the guide member on the shuttle mounting to effect precise movement of the latter in
15 said support; and means for reciprocating the shuttle mounting in said support.
7. In a hosiery embroidery machine, a pattern actuated hosiery holding frame; embroidery mechanism cooperatively associated with said frame and comprising a yarn shuttle; a movable shuttle mounting; a support for said mounting provided with a slideway for the shuttle mounting; a guide rib on said mounting extending lengthwise thereof; a guide groove ex-
20 tending lengthwise of the support in which the said guide rib is arranged to slide to effect precise movement of the shuttle mounting; and means for reciprocating the shuttle mounting in said support.
8. In a hosiery embroidery machine, a pattern actuated hosiery holding frame; embroidery mechanism cooperatively associated with said frame comprising a yarn shuttle; a movable shuttle mounting; a support for said mounting
25 provided with a slideway for the shuttle mounting at its upper end and a plurality of slide rod guides; a guide rib on said mounting extending lengthwise thereof; a guide groove ex-
30 tending lengthwise of the support in which the said guide rib is arranged to slide to effect precise movement of the shuttle mounting; a link connecting the upper end of the slide rod and the shuttle mounting; and an actuator having a composite movement in contact with said anti-friction roller.
9. In an embroidery machine, the combination with pattern controlled fabric positioning means; of embroidering mechanism comprising a yarn shuttle; a movable shuttle mounting; a guide for determining the movement of said mounting; means for actuating said mounting including an actuator, a movement transmitting member movable at an angle with respect to the movement of said mounting provided with length adjusting means, and a motion translating ele-
35 ment connecting said member and mounting.
10. In an embroidery machine, the combination with fabric positioning means; of embroidering mechanism comprising a yarn shuttle; a movable shuttle mounting comprising means for retaining the shuttle in place in said mounting and a spring positioned shuttle release member; a guide for determining the movement of said mounting; means for actuating said mounting including an actuator, a movement trans-
40 mitting member movable at an angle with respect to the movement of said mounting, and a motion translating element connecting said member and mounting.

JOSEPH C. GILARDONE. 40
